UNITED STATES PATENT OFFICE.

SAMUEL S. WELLS, OF LYNN, MASSACHUSETTS, ASSIGNOR TO WELLS-ODELL NOVELTY COMPANY, OF LYNN, MASSACHUSETTS.

DESIGN FOR A WASTE-RECEPTACLE.

47,635.

Specification for Design.

Patented July 20, 1915.

Application filed May 26, 1915. Serial No. 30,690. Term of patent 14 years.

To all whom it may concern:

Be it known that I, SAMUEL S. WELLS, a citizen of the United States, residing at Lynn, in the county of Essex and State of Massachusetts, have invented a new, original, and ornamental Design for Waste-Receptacles, of which the following is a specification, reference being had to the accompanying drawing, forming a part thereof.

The figure is a perspective view of a waste receptacle showing my design.

I claim:

The ornamental design for a waste receptacle as shown.

SAMUEL S. WELLS.
